UNITED STATES PATENT OFFICE.

PETER W. SAMUELSON AND WILLIAM CHRISTOFFERSON, OF PEPIN, WISCONSIN.

TORSION-TUBE HOIST AND HOLDER.

1,392,971.

Specification of Letters Patent.

Patented Oct. 11, 1921.

Application filed December 27, 1920. Serial No. 433,218.

To all whom it may concern:

Be it known that we, PETER W. SAMUELSON and WILLIAM CHRISTOFFERSON, citizens of the United States, residing at Pepin, in 5 the county of Pepin and State of Wisconsin, have invented certain new and useful Improvements in Torsion-Tube Hoists and Holders; and we do hereby declare the following to be a full, clear, and exact description of the invention, such as will enable others skilled in the art to which it appertains to make and use the same.

This invention relates to a device for lifting the torsion tube of an automobile and 15 holding the same in lifted position during the removal and replacement of the engine. The device is particularly adapted for use on a Ford or similar type of automobile. When it is desired to remove the engine from 20 such an automobile, it is necessary to lift the torsion tube in order that the same may be disconnected. This has heretofore been done by a jack placed upon the ground. Such a procedure involves working in disadvantageous and uncomfortable position and prevents any desirable movement of the car.

It is an object of this invention, therefore, to provide a device for lifting and holding the end of the torsion tube by the 30 use of which the engine can be removed and, if desired, the car may be moved on the ground or floor while the torsion tube is still held in its elevated position.

It is a further object to provide such a device by which the elevation of the torsion tube can be quickly changed or adjusted and the replacement in the engine thus facilitated.

These and other objects of the invention 40 will be readily apparent from the following description made in connection with the accompanying drawings in which like reference characters refer to the same parts throughout the different views, and in 45 which,

Figure 1 shows somewhat diagrammatically the frame and wheels of a Ford car, a torsion tube thereon and applicant's device in position for use;

50 Fig. 2 is a view in elevation looking at the side of the car frame and also showing the device in use with the torsion tube; and

Fig. 3 is a view of the device in elevation as seen from the right in Fig. 1, a portion 55 thereof being shown in section.

Referring to the drawings, the device is

seen to consist of a cross member or beam 1, the ends of which are tapered toward the outer ends in thickness and have secured at such ends transversely thereof, short blocks 60 2 which project a short distance at either side of the member 1. A nut member 3 is disposed in an aperture located centrally of the member 1, which nut member has a flange extended at each side thereof in its 65 upper end by which it is attached to the member 1 by screws or other suitable fastening means which pass through holes in said flange. A screw 4 provided at its upper end with an operating crank is arranged to 70 pass vertically through the nut member 3 and is formed at its lower end to constitute the ball member of the ball and socket swivel joint, the socket member of which comprises a transversely extended hook member 5 75 formed of two similar parts which are connected by suitable bolts or screws 6. A chain 7 is fastened to one of the bolts 6 of the member 5 and is adapted to have one of the links thereof hooked over the hook of 80 member 5 when the device is in use.

The operation and use of the device is illustrated in Figs. 1 and 2. In Fig. 1 is shown in plan a diagrammatic representation of the frame and wheels of a Ford car 85 which comprises a torsion tube *a*, the frame members *b*, and the connection *c* between the end of the torsion tube and the engine.

When it is desired to lift the torsion tube, the member 1 is placed across the frame of 90 the automobile with the members 2 resting on the frame members *b*. The screw 4 is lowered to a suitable position and the chain 7 is then passed around the end of the torsion tube and a link thereof hooked over 95 the hook of member 5. The torsion tube 5 will then be elevated as desired, by turning the crank and raising the screw 4. The engine and its shaft can then be quickly and conveniently removed and the lifting device will remain in position on the car and hold the torsion tube elevated. The car can 100 then be moved, as desired, without any further securing of the torsion tube. This movement of the car without securing the torsion tube could not be accomplished if the tube had been raised by a jack placed 105 on the floor. When it is desired to replace the engine, the tube can be lowered or adjusted in height to facilitate the connection 110 by turning of the crank of screw 4. The operator will be above the torsion tube and

can conveniently operate the device and at the same time assist in making the connection at the usual universal joint.

It is thus seen that applicant has provided 5 a simple device having great utility and which greatly facilitates the described operation on the automobile. The device can be manipulated by the operator while in a convenient position, and as stated, the device can remain in position on the car and the latter be moved to any desired location. It will, of course, be understood that changes in the form and details of the device can be made without departing from 10 the scope of applicant's invention, which, generally stated, consists in the matter shown and described and set forth in the appended claims.

What is claimed is:

- 20 1. A device of the class described having in combination a member adapted to extend between and be supported upon the side frame members of an automobile, an elevating device carried by said member at the central portion thereof, and means at the lower end of said elevating device constructed and arranged to embrace and support the torsion tube of the automobile when the elevating device is operated.
- 25 2. A torsion tube lifter and holder for Ford automobiles having in combination a member adapted to extend across and rest upon the side frame members of an automobile, an elevating means extending through said member centrally thereof, a head swivelly mounted upon the lower end of said elevating means below said member having attached at one end thereof a chain, and having its other end formed as a hook

over which a link of the chain is adapted 40 to be secured.

3. A torsion tube lifter and holder having in combination a beam member adapted to extend transversely of and be supported by the side frame members of an automobile, a 45 nut disposed in said beam centrally thereof, an elevating screw extended vertically through said member and nut and a swiveling head connected to the lower end of said screw and extending transversely thereof, 50 said head having a chain secured at one side thereof and having its other side formed as a hook member over which a link of the chain is adapted to be disposed.

4. A device of the class described having 55 in combination a cross beam adapted to extend across the frame of an automobile, blocks secured at the underside of said member at the ends thereof and extending transversely of said member, a flanged nut secured in an aperture formed centrally of said cross member, a screw arranged to travel in said nut having an operating means at one end thereof, a head connected to the lower end of said screw by a ball and socket 60 joint and extending at each side thereof, a chain secured to one side of said head having its other end free, said head being formed at its other side with a hook over which a link of said chain is adapted to be disposed. 70

In testimony whereof we affix our signatures in presence of two witnesses.

PETER W. SAMUELSON.
WILLIAM CHRISTOFFERSON.
